UNITED STATES PATENT OFFICE.

BRADLEY WOODHULL, OF DUNMORE, PENNSYLVANIA, ASSIGNOR TO THE SCRANTON STOVE WORKS, OF SCRANTON, PENNSYLVANIA.

DESIGN FOR A HEATING-STOVE.

SPECIFICATION forming part of Design No. 28,820, dated June 7, 1898.

Application filed February 25, 1898. Serial No. 671,699. Term of patent 14 years.

To all whom it may concern:

Be it known that I, BRADLEY WOODHULL, a citizen of the United States, residing at Dunmore, in the county of Lackawanna and State 5 of Pennsylvania, have invented and produced a new and original Design for Heating-Stoves, of which the following is a specification, reference being had to the accompanying drawing, forming a part thereof.

- The drawing represents in perspective view a stove embodying the present design.

The leading feature of the design consists in the ornamentation and configuration of the stove, as will now be described and the particular features of novelty pointed out in the claims hereto appended.

- The letter A indicates the base of the stove, having the legs *a*, the base and the legs being covered by the scroll-like ornamentation, as shown. Above the base is the top base-section B, having the corner ornaments *b* and fluted ornamentation on the sides and front and the plain band *b'* along the bottom edge.

The ash-pit section of the stove is provided 5 at the front with the ash-pit door C, ornamented with the two scrolls *c c*, separated at the center by the ornaments *c' c'*. On the side of the ash-pit section are the panels C', having the scroll-like ornamentation thereon.

- Carried by these panels are the rounded rails C², having the circular ends covered with the scroll ornamentation and having two arms or projections *c² c²* on the upper side and two arms *c³ c³* on the lower side, all ornamented 5 as shown.

C⁴ is the top plate of the ash-pit section, having the fluted ornamentation C⁵ at the sides and the corner ornaments C⁶ and covered with the scroll ornamentation at the 5 front.

- The central section of the stove has the rounded curved band F, bearing the scroll ornamentation, as shown. Below this band on the side is a lower side door D, which is 5 curved outward, both in the direction of its height and width, and is provided with six upper mica openings *d* and three larger mica openings *d'* below these and the rosettes or buttons *d²* on the central longitudinal dividing-strip. Below the band F in front is a door formed of two leaves D², each leaf curved

outward in the direction of its height and width and having the six small mica openings *d³* and three large mica openings *d⁴* below these and the rosettes or buttons *d⁵*. 55 Above the band or zone F at the side is the upper side door E, curved outward in the direction of its width and height and provided with the six mica openings *e* and carrying the scroll ornamentation *e'*, as shown. 60

Above the band F at the front is a door of two leaves E², each curved outward in the direction of its height and width and provided with six mica openings *e²* and carrying the scroll design *e³*. 65

H indicates pillars or posts vertically fluted, of which there are two on each side of the body-section of the stove, curved to conform to the curvature of the band F and doors, as shown. 70

The jacket J is curved upwardly and outwardly at the sides and front, while at the corners it extends down upon the body and covers the upper ends of the fluted columns H, being covered with the scroll ornamentation. 75

The top ring K rests upon the jacket J, being covered with the scroll ornamentation, harmonizing with that of the jacket, the edge of the ring following the outline of ornamentation of the body portion of ring and lapping slightly over the top of the jacket, whereby the jacket and ring appear as one body and the ornamentation of each as a single design. 80

L is a dome-shaped cover covered with the scroll ornamentation, as shown, and carrying the ornament M. 85

Having thus fully described my invention, what I claim as new, and desire to secure by Letters Patent, is— 90

1. In a design for a stove, the design for the base; substantially as shown and described.

2. In a design for a stove, the design for the top base-section D; substantially as shown and described. 95

3. In a design for a stove, the design for an ash-pit section; substantially as shown and described.

4. In a design for a stove, the design for the ash-pit door; substantially as shown and described. 100

5. In a design for a stove, the design for the body-section; substantially as shown and described.
6. In a design for a stove, the design for 5 the lower front door; substantially as shown and described.
7. In a design for a stove, the design for the upper front door; substantially as shown and described.
- 10 8. In a design for a stove, the design for the jacket; substantially as shown and described.
9. In a design for a stove, the design for the top ring; substantially as shown and described.
10. In a design for a stove, the design for the cover L; substantially as shown and described.
11. The design for a stove, as substantially herein shown and described.

BRADLEY WOODHULL.
